UNITED STATES PATENT OFFICE.

JOSEPH SCHLICHTINGER, OF ATLANTA, GEORGIA.

SELF-FEEDER AND DRINKING-FOUNTAIN FOR POULTRY.

1,091,392.

Specification of Letters Patent.

Patented Mar. 24, 1914.

Application filed November 4, 1913. Serial No. 799,245.

To all whom it may concern:

Be it known that I, JOSEPH SCHLICHTINGER, a subject of the Emperor of Austria-Hungary, resident of Atlanta, in the county 5 of Fulton and State of Georgia, have made a certain new and useful Invention in Self-Feeders and Drinking-Fountains for Poultry; and I declare the following to be a full, clear, and exact description of the same, 10 such as will enable others skilled in the art to which it appertains to make and use the invention, reference being had to the accompanying drawings, and to letters or figures of reference marked thereon, which 15 form a part of this specification.

Figure 1 is a side view of the invention partly in section. Fig. 2 is a plan view of the invention with jar removed. Fig. 3 is a detail side view of the lower portion of 20 the feeder, with the inner ring removed. Fig. 4 is a detail side view of the inner ring.

The object of the invention is to provide an improved poultry feeding trough and fountain, and the invention consists in the 25 novel construction and combinations of parts, as hereinafter set forth.

In the accompanying drawings, the numeral 2, designates the inward and upward inclined conical base of the trough, which is 30 preferably of circular form, having a cylindrical wall 3, rising vertically an inch or so from the edge of the inclined base to which it is attached. From the top of this vertical wall 3, extends upward and inward 35 over the outer portion of the conical base, an inclined conical wall 4 of the trough, which terminates at the top of a circular seat 5, above the central and higher portion of the inclined base. The inclination of this 40 wall 4, is about forty-five degrees, and its breadth is sufficient for the circular feed apertures 6, which are made through this wall. The conical base serves to cause the grain or feed to take position near the 45 apertures of the inclined wall, which are located over the outer or lower portion of the conical base. The upper edge of this inclined wall is provided with substantially 50 horizontal lugs or bearings 7 which project outward and are separated by disengagement intervals between their ends.

Within the circular seat 5, is a detachable 55 concave or inward inclined circular connection or supporting ring 8, having similarly separated outward projecting catches 9, attached to its upper edge portion and adapted

by means of hook shaped flanges to engage the bearings 7, of the inclined wall 4, when turned in one direction. But when turned in the opposite direction, to bring the flanges 60 to the intervals between the lugs 7, the supporting ring 8, becomes disengaged, so that the parts of the device can be thoroughly cleaned.

The lower portion of the wall of the ring 65 8, projects downward below the level of the apex of the conical base 2 is provided with a screw thread or bearing for engagement with the neck of a preserving or other jar, designed to serve as a reservoir or fountain, 70 and having a coöperating thread or bearing; and the ring is designed when connected to the trough to hold such jar securely in position bottom upward, so that whatever grain or other small feed, or water has been 75 placed in the jar, will feed downward upon the conical bottom or base 2, whereby it will be guided downward and outward to position under the inclined wall 4. To this end, the ring 8, is supported to extend 80 downward within the trough so that its lower edge is located above the conical base a short distance, about a quarter of an inch more or less whereby a narrow circumferential feed passage is provided from the jar to 85 the outer portion of the trough chamber.

This feeder is designed for cleanliness, especially in the fact that the inclination of its aperture wall is such as to prevent the chickens from standing thereon, which they 90 would do if a foothold were to be had. The inclination of the wall 4, is otherwise important, because the feed apertures can be made of exact size to admit the heads of 95 little chickens, and to exclude the heads of larger fowl. The inclined position of the apertures also tends to prevent the feed from being scratched out. By the use of this device, where the feed apertures are made of small size, it is designed to prevent the 100 loss of many small chickens, as it is very difficult to separate them from larger fowl. It will tend also to keep them in good health and condition, as the larger fowl cannot interfere and take up the feed.

I claim:

1. In a feeder for poultry, a trough having an upward and inward inclined conical base connected to a vertical circular wall, an upward and inward inclined circular extension of said wall having a series of inclined circular feed apertures, and in sepa-

rable engagement with said extension a downward and inward inclined supporting ring extending below the top of the conical base and provided with means for engaging 5 a fountain jar.

2. A feeder for poultry, comprising a cylindrical trough having an upward and inward inclined conical base, an upward and inward inclined circular wall over said base 10 provided with inclined circular feed apertures, a central opening and catch devices around said opening, a reservoir having its mouth portion projecting downward within

the trough below the top of the conical base, and a downward and inward inclined supporting ring having lower means of engagement with the reservoir mouth portion and upper catch devices separably engaging the catch devices of the inclined circular wall of the trough. 15

In testimony whereof I affix my signature, in presence of two witnesses.

JOSEPH SCHLICHTINGER.
